(57) **CLAIM**

The ornamental design for a radiotherapy machine having a display screen, as shown and described.

DESCRIPTION

FIG. 1 illustrates a front perspective view of a radiotherapy machine having a display screen;

FIG. 2 illustrates a front perspective view thereof in a rotated state;

FIG. 3 illustrates a left elevation view thereof;

FIG. 4 illustrates a right elevation view thereof;

FIG. 5 illustrates a top plan view thereof; and,

FIG. 6 illustrates a bottom plan view thereof.

The broken lines illustrate environmental structure and portions of the radiotherapy machine having a display screen, and form no part of the claimed design.

1 Claim, 6 Drawing Sheets
